UNITED STATES PATENT OFFICE.

PAUL DU BUIT, OF PARIS, FRANCE.

POWDER CHARGE.

SPECIFICATION forming part of Letters Patent No. 683,106, dated September 24, 1901.

Application filed September 27, 1900. Serial No. 31,328. (No specimens.)

To all whom it may concern:

Be it known that I, PAUL DU BUIT, civil engineer, of the city of Paris, 13 Rue Auber, in the Republic of France, have invented new and useful Improvements Relating to Charges of Powder, which improvements are fully set forth in the following specification.

This invention relates to accelerating charges for ordnance, and has reference to improved forms and arrangements of the elements of charges of powder, the advantages of which were not recognized at the date of my previous application for Letters Patent No. 2,509, of January 23, 1900, and were not therefore particularly described therein.

The object of my invention is to provide a powder that shall be "slow-burning," as that term is understood in this art, so as to produce an accelerating effect, and to accomplish this result I break the continuity of the mass of the powder by employing one or more sheets of powder of a suitable composition, each of which sheets carries a number of elongated projections, to be then rolled up to form the charge. The idea (as in my pending application above noted) is to present to the action of the detonator a gradually-increasing combustion-surface, and in addition in the present invention I rely not only on the taper of these elongations, but also upon the varying thickness of the sheet itself and on the difference in thickness and height of the several sheets where a plurality of sheets is employed.

According to the present invention the charge comprises substantially one or more sheets of powder which may be of a suitable thickness and of various shapes, according to the results to be attained by the combustion of the charge. Each sheet is cut or otherwise shaped so as to resemble a comb with teeth of any suitable length and width, spaced as required, which teeth may terminate in points or in fringes of any suitable length, pointed or not.

Figure 1 illustrates a plurality of sheets A and B of varying thickness partly rolled up. Figs. 2 to 6 show sheets A' to A⁶, respectively, cut in different forms, but not rolled. Figs. 7 and 8 are end views illustrating sheets of varying and of respectively different thickness.

The teeth may be of any suitable shape, as

triangular, rectangular, polygonal, regular, or irregular, and the sheets may be rolled up, if required. The teeth may be arranged close together, so that there is no space between them for the greater part of their length when the sheet is flat, but that spaces are formed between them when the sheet is rolled up. In some cases notches or grooves may be formed on one side of the sheet—that is to say, the notches or grooves do not extend completely through the sheet—in which case the sheet should be rolled up with the notches or grooves on the outside. Furthermore, the teeth may be of equal or of very unequal and gradually-increasing width. The sheet of powder may be of uniform or variable thickness and may gradually increase in height and in length, while the charge may be composed of several superposed sheets of powder of the same thickness or of different thicknesses placed one upon another and rolled up together or separately. Finally, the charge hereinbefore described may or may not occupy all the available height, according to circumstances, and it may advantageously have a height a little greater than the cartridge, so that in consequence of the pressure of the projectile the comb-teeth are spread in such a manner as to be favorable to combustion.

The several forms of elements hereinbefore described have a considerable influence on the combustion of the powder under pressure, and by selecting them judiciously the requirements of the projectile may be reasonably complied with.

Having now fully described and ascertained the nature of my invention, I declare that what I claim is—

A charge of powder consisting of a plurality of sheets of suitable composition and of varying thickness, the said sheets provided with tapering elongations and being rolled up to present all of said elongations in the same direction, substantially as and for the purpose described.

In testimony whereof I have signed this specification in the presence of two subscribing witnesses.

PAUL DU BUIT.
